Application November 10, 1951, Serial No. 255,779

13 Claims. (Cl. 242—35.5)

1

The present invention relates to textile winding machines and comprises a novel machine of this type which has a high output per square foot of floor space, is substantially noiseless in operation, is economical to construct and operate, easy to replenish and doff and operates with a minimum of "ends down." The machine winds uniform and accurate packages without "hilling" at the ends of the bobbins, without "ridging" along the barrels of the bobbins, and the traverse means thereof may be readily changed for winding of different shaped packages. The machine of the invention is an improvement over the redraw machine described and claimed in applicant's copending application Serial No. 131,538, filed December 7, 1949.

The new machine is of circular configuration with the drive means located in the central portion of the machine, the rotating spindles carrying the bobbins to be wound arranged in a circle about a central support post and with the supply creel arranged in an outer circular zone. The traverse means, which rotates unidirectionally about the central support post in a circular path between the creel and the spindles, is of the general type of that of the machine described and claimed in the said copending application in that it comprises a member having an edge contoured in a series of hills and dales over which the yarn from the supply packages is led in transit to the spindles.

For a better understanding of the invention and of a preferred embodiment thereof, reference may be had to the accompanying drawings, of which—

Fig. 1 is a perspective view, partly broken away and with some details omitted, of a machine embodying the invention;

Fig. 2 is a fragmentary top plan view of the machine of Fig. 1 with the cover removed to show the drive mechanism;

Fig. 3 is a vertical sectional view, partly in elevation, of the machine of Fig. 1;

Fig. 4 is a detail side view of a single spindle showing the drive and brake therefor; and

Figs. 5 and 6 are horizontal and vertical sectional views, respectively, of the means for cyclically varying the relation between the rate of rotation of the spindles and the rate of travel of the traverse means.

A general description of the new machine will first be given with reference to Fig. 1. The machine includes a lower cylindrical casing or skirt 2 which carries the supply creel and an outer circular guard rail 4. The skirt is mounted on a base 6 adjustably supported above the floor on foot pads 8. An upper skirt 10 of larger diameter, which is supported from the upper portion of the skirt 2 by a support ring 11 of wood or the like, terminates about its upper periphery in an outwardly flaring shield 12 for the rotary

2

traverse means 14, the shield being double-walled and provided with a plurality of yarn guide slots 16. A plurality of spindles, take-up bobbins on which are indicated at 18 in Fig. 1, are rotatably supported adjacent the inner wall 20 of the slotted guard 12 with their axes inclined to the vertical and generally parallel to the slots 16, there being one slot 16 for each spindle. A cylindrical cover 22 having a slightly domed top encloses the drive means for the traverse rotor and for the spindle drive belt. The traverse means 14 rotates in the annular space defined by the inner and outer walls of the shield. It has an upper yarn engaging edge 24 that is so contoured as to form a series of hills and dales. In the particular embodiment of the invention illustrated in the drawings, the traverse means is shaped for the winding of cylindrical packages and therefore the slope of the edge 24 between a peak 26 of a hill and the bottom 28 of the next succeeding dale is uniform. The peak 26 of each hill is aligned with the upper ends of the barrels of the bobbins to be wound and the bottom 28 of each dale is aligned with the lower ends of the bobbin barrels so that, as the contoured edge 24 travels by a bobbin, the yarn travels up and down in the guide slot 16 associated with that bobbin and traverses the full length of the barrel.

Interposed in the yarn flow path between the supply creel and the guide slots 16 are yarn guide and tensioning means each comprising two pigtail guides 29 and two disk tension devices 30 mounted on a slotted base 32. Each base 32 rests on a rail 36 supported by radially disposed brackets 38 secured at their inner ends to the under side of the support ring 11, the rail 36 passing through the slots in the bases 32.

The guard rail 4 is mounted on the outer end of a plurality of pairs of brackets 40 and 41, the inner ends of which are secured to the skirt 2. Each bracket 41 carries an upstanding pin 42 by means of which a yarn supply package, such as indicated by the reference numeral 44 in Fig. 1, is supported on the bracket. Brackets 46 mounted on the skirt 2, carrying angularly disposed pins 48, serve to support additional supply packages and complete the creel.

Referring now to Fig. 3, it will be noted that the machine is built around a central hollow bored post 50 which is supported on the base 6 by bolts 52 and which has mounted thereon by means of bearings 54 a rotatable sleeve 56. The sleeve 56 by means of tension rods 58 and collar 59 supports a rotor platform 60 on the upper outer surface of which are mounted two traverse support rings 62 and 64 each of which has an inclined surface to which the segments of the traverse rotor 14 are secured by screws as shown in Fig. 3, ring 62 being of larger diameter and supported above the platform 60 by spacers 66 which insure that the traverse engaging surfaces

of rings 62 and 64 are in proper relation corresponding to annuli of a conical surface. The sleeve 56, platform 60 and traverse means 14 are rotated about the axis of the post 50 through the intermediary of an annular gear 68 which is mounted on the platform 60 with its center at the axis of the post and with teeth on its outer periphery in engagement with a drive pinion 70. Pinion 70 is carried on the lower end of a shaft 72 journaled at its lower end in bearings mounted in the main support platform 74 of the machine and at its upper end in bearings mounted in a change gear arm 76. Shaft 72 carries a gear 78 at its upper end, the drive means for which will presently be described.

The main platform 14 is supported from the central post 50 by means of radial vanes 80 to which the platform is welded and which in turn are welded or otherwise securely fastened to a sleeve 82 on the post 50. The sleeve 82 is supported by bolts 84 from a main mounting platform cap 86 disposed on the upper end of the post and setscrews 85 threaded through the sleeve into engagement with the post. A spindle mounting ring 88, comprising an annular plate, is mounted on the upper surface of the platform 14 adjacent the periphery thereof and mounted on this ring at spaced positions are spindle brackets 90, each of which extends beyond the periphery of the platform 14 and is bent downwardly. Spindle bolsters 92 are mounted in openings in the downwardly extending portions of the brackets 90. Beyond the bolster carrying location each bracket 90 is curved upwardly, as shown best in Fig. 4, and is provided with a stud 96 on which is mounted an idler pulley 98. The whorls 100 of the spindles are driven by an endless V-belt 102, the outer side of which engages the idler pulleys 98, the belt engaging each whorl over a relatively small angle.

Carried by the upper end of each whorl 100 for threadwise adjustment axially thereof is a three-cornered spider or dog 97 which can be rigidly clamped at any desired position to the whorl 100 by means of a screw 99 extending through lugs provided on the spider 97. A neoprene drive spacer 101 is affixed to the dog 97 at each corner thereof, there being, of course, three spacers associated with each dog. The bobbins 18 and 18', supported by spindles, seat against the spacers 101, being held by gravity in frictional engagement therewith. It will thus be seen that a driving connection between the bobbins 18 and whorls 100 are rotated by belt 102, the bobbins will be also rotated.

By virtue of the above arrangement one of the essential features of my invention is accomplished, i.e., accurate and precise positioning of the bobbin with respect to the yarn traverse means 14. Manifestly, even the most controlled delivery of yarn to the bobbin would not result in a correctly wound bobbin unless the bobbin itself were properly positioned relative to the yarn delivery means. By permitting the dog 97 to be adjusted axially of the spindle its position relative to yarn traverse 14 can be determined within a few thousandths of an inch.

It will be appreciated that my invention is capable of use with bobbins of different types and configurations. To this end, I have shown in Figure 1 my device in association with bobbins of the conventional M-100 revolving type and in Figures 2, 3 and 4 with bobbins of the two-for-one type, it being necessary to use an adapter 103 with the latter type.

The drive motor 104 for the machine is mounted above the platform 14 on a pedestal 106. The motor, through a conventional variable speed pulley unit 107, having the hand wheel 108 for manual adjustment, belt drives a pulley 110 fixed on the horizontal shaft of a miter gear box 112. A double grooved sheave 114 and a variable speed pulley 116 are fixed on the vertical driven shaft 117 of the gear box (see Figs. 2 and 6). Belt 102 passes around a double grooved idler pulley 118 and belt tensioning idler pulley 120 rotatably mounted in one end of an arm 122. Arm 122 is pivotally mounted at 124 on the main platform 14 and connected at its other end to a tension spring 126 the other end of which is connected to a bracket 128 adjustably mounted on the cap 86.

The variable speed pulley 116 on vertical shaft 117 belt drives a pulley 130 which, through a gear 132 on its shaft, drives gear 78 on shaft 72, shaft 72 through pinion gear 70 and annular gear 68 driving the traverse rotor as hereinbefore described. An idler reversing gear 133, mounted on a stud carried by the change gear arm 76, is provided for reversing the direction of rotation of the traverse rotor with respect to the direction of rotation of the spindles.

In order to prevent ridging of the packages, a cyclical variation of the traverse rotor rate of rotation is introduced by the means shown in Figs. 5 and 6, to which reference may now be had. The variable speed pulley 116 on the vertical shaft 117 of the miter gear box has a fixed upper sheave 116a and a movable lower sheave 116b, the bearing cup 134 for which is carried by a cam follower plate 136. Plate 136 is pivotally mounted on dowel pins 138 fixed in brackets 140 on a base plate 142 covering the miter gear box. A vertical shaft 144 is mounted in bearings carried by the base plate 142 and by a housing 146. Fixed to this shaft is a large gear 148 and a worm gear 150. Gear 148 meshes with, and is driven by, gear teeth formed on a sleeve 152 fixed to the shaft 117. Worm gear 150 drives a worm wheel 154 fixed to a horizontal shaft 156 journaled at its ends in bearings carried by the brackets 140. A cam 158, which is eccentrically mounted on the horizontal shaft 156, is shaped to engage and rock the cam plate follower 136 at each revolution of shaft 156. Thus, with the above described arrangement, the movable sheave 116b is raised and lowered by the cam plate follower to vary correspondingly the pitch ratio between pulley 116 and 130 and the rate of rotation of pulley 130 and therefore of the traverse rotor.

Each spindle is provided with individual manually controlled braking means for doffing, replenishing and piecing up of ends. These means, as best shown in Fig. 4, comprise a brake shoe 160 mounted on the end of an arm 162 and adapted to be brought into braking engagement with the spindle whorl 100. The arm 162, which is pivotally mounted on the spindle bracket 90, is coupled by a looped spring wire 164 to a collar 166 threaded for adjustment onto the end of a pivoted lever 168, the ends of the wire being sprung into holes in the arm 163 and through collar 166 and being sprung outwardly to clear the spindle whorl as shown best in Fig. 2. Lever 168 is pivotally mounted at its lower end on a pin 170 which is fixed at its ends in upstanding spaced support walls 172a and 172b. The walls 172a and 172b are mounted on the spindle bracket 90 as by rivets 174. A manually operable arm

176 is fixedly secured to lever 168 or formed integral therewith, a knob 178 being mounted on the free end of the arm. Thus when an operator moves the arm 176 in the direction of the arrow in Fig. 4, that is, away from the spindle, the collar 166 pulls spring wire 164 which in turn pulls the brake shoe 160 into braking engagement with the whorl 100 stopping the spindle, overcoming driving belt means 102. Rivets or pins 180 and 182 maintain the walls 172a and 172b in spaced relation and serve as limit stops for lever 168.

Mounted on the lower skirt 2 of the machine is a switch box and plug-in unit 184 and reversing switch 186 for the motor 104, the wiring to the motor being omitted from the drawings.

In order to insure proper alignment of the guide slots 16 with the spindles, means are provided for adjusting through a limited angle the position of the spindle mounting ring 88. These means comprise a rack 188 (see Fig. 2) fixed to the ring 88 and a cooperating drive pinion therefor mounted in a bracket 190 fixed to the platform 74, an operating unit for the shaft of the pinion being indicated at 192. Arms 194 and 196 fixed to the ring 88 and extending over the platform 74 carry bolts 198 and 200, respectively, which, by engagement with one of the vanes 80, serve as adjustable limit control stops for the ring 88.

In threading up the above described running machine, the operator, after braking a spindle by movement of arm 176 draws an end of yarn from a supply package 44, threads the end through one guide 29, then between the disks of each pair of tension disks 30, out through the other guide 29 and then wraps the end for a few turns around an empty take-up bobbin 18. The bobbin is then placed on the spindle with the yarn passing through the associated slot 16 in the traverse shield 12. Upon releasing the spindle brake by manipulation of arm 176, or upon energization of motor 104 by switch 184 if the machine had not previously been placed in operation, rotation of the spindle takes up slack in the yarn and thereby brings it into engagement with the contoured edge 24 of the traverse rotor. Rotation of the traverse rotor, effected through the means heretofore described, causes the yarn to ride up and down in the slot 16, traversing the bobbin and, with the particular contour of traverse rotor illustrated, building a cylindrical package. When there is substituted for the particular traverse rotor illustrated, one in which the upper edge on both sides of a peak is curved concavely, the upper part of the barrel of a bobbin will be traversed at a higher rate than the lower part of the bobbin and hence a tapered package is formed as described in the said copending application. During building of the package, tracking of one layer of yarn on the preceding layer, which results in ridging of the winding, is avoided by a plus and minus 5 per cent cyclical variation of the rate of rotation of the traverse rotor, resulting from the periodic movement of the lower sheave 116b by the cam plate follower 136 as heretofore described. "Hilling," ridging or patterning as it is sometimes called, by proper contouring of the yarn guiding edge of the traverse means 14. It will be apparent that in a traversing operation the yarn must be delivered to the bobbin at a slight angle with respect to a plane perpendicular to the bobbin axis, which angle is termed the "lead angle." By changing the lead angle, the number and spacing of helices of yarn

wound on a given bobbin can be varied as desired. In the case of the "parallel wind" bobbin, it is contemplated that the traverse means 14 will be so contoured as to maintain the lead angle constant as the flange of the bobbin is approached and to reverse such angle instantaneously at the moment the yarn contacts the flange. As a result of the yarn being the only element in reciprocation, the inertia of the system is negligible which permits extremely high acceleration and deceleration and, consequently, accurate full flange to flange winding in each cycle of the operation without "trapping" of the yarn at the flanges, at higher winding speeds than has heretofore been practical.

From the foregoing description of the illustrated machine and of the operation thereof, it will be apparent that the invention provides a practical and efficient textile winder. Due to the circular configuration with the parts primarily supported from a central post, a mechanically rugged machine is obtained. The unidirectional travel of the traverse rotor insures relatively silent and rapid operation and the disposition of the supply creel on the main skirt permits easy access thereto by the attendant for replenishing and piecing up of ends. The circular construction with the central hollow post permits of ready lubrication of the moving parts and the removable domed cover permits of access to the drive mechanism for inspection, replacement or adjustment.

The following information relating to a machine constructed in accordance with the invention is indicative of the superiority of the new circular machine as compared to conventional machines now in wide use in textile mills.

The particular machine is about seven feet in diameter at the guard rail and about five feet from floor to top of cover. There are 29 spindles set at 35 degrees with respect to the vertical. The take-up bobbins have a traverse length of four and one-half inches and a barrel diameter of two and one-fourth inches. The speed range is from 720 to 4800 R. P. M. which, for the particular bobbins used, corresponds to an average of 180 to 1200 yards per minute. As compared to a conventional winder now in common mill use, there is a direct saving in labor as the time required for doffing and replenishing the new machine is substantially less for the new machine. The cost of fixing labor, due to the absence of conventional reciprocating traverse means, is reduced substantially by one-third with the new machine. Breaks per cake at the new winder are about one-half the conventional winder and breaks at the twister when twisting yarn wound on the new machine are substantially less than when twisting yarn wound on the conventional machine. The average practical yarn speed of the new winder is many times that of the conventional machine (75 denier viscose cakes are run at 700 yards per minute on the new machine as compared with 180 yards per minute on the conventional machine), resulting in substantial saving in overhead and in indirect labor cost and in greatly increased output per spindle hour. Above all, the packages found on the new machine are superior to those wound on the conventional machine, resulting in elimination of rejects with their attendant waste in material and labor. The invention has now been described with reference to one specific embodiment thereof. Obviously, various changes in the particular construction

illustrated and described could be made without departing from the spirit of the invention or the scope of the accompanying claims. For example, the variable speed drive of the spindle drive belt could be obtained by means other than variable speed pulleys, as for example by means of a simple cone pulley and V-belt with means for shifting the locations of the belt on the pulley, or a change gear mechanism could be incorporated in the power transmission. Also instead of the particular individual spindle braking means described and illustrated, other means for braking the spindles or for disengaging them from the drive belt could be provided. Other modifications will be apparent to those skilled in the art.

The following is claimed:

1. A textile winding machine comprising in combination a vertically disposed post, a supply creel disposed about said post, a circular platform supported by said post and above said creel, a plurality of rotatable spindles arranged on said platform in a generally circular array about the post as an axis, a traverse rotor rotatably mounted on said post below said platform, said rotor having a contoured edge positioned for travel of yarn thereover in transit from packages in said creel to take-up bobbins on said spindles, and means carried by said platform for rotating said spindles about their respective axes and for rotating said traverse rotor about the axis of said post.

2. The machine according to claim 1 wherein said last-mentioned means includes a driven shaft, a pair of pulleys fixed to said shaft, a spindle drive belt in driving engagement with one of said pulleys and said spindles, and means for driving said traverse rotor from the other of said pulleys.

3. The machine according to claim 2 wherein one of said pair of pulleys on said shaft is a vari-pitch pulley and wherein cam means actuated by rotation of said shaft are provided for varying the pitch of said vari-pitch pulley to vary cyclically the ratio between the rate of rotation of the spindles and the rate of rotation of the traverse rotor and thereby prevent hill-ing of yarn on the take-up bobbins.

4. A textile winding machine comprising a vertically disposed central post, a circular support platform carried thereby, a plurality of spindle mounts carried by said platform and extending radially therefrom, a spindle rotatably mounted on each mount with its axis inclined to the horizontal, a drive belt encircling said spindles and in driving engagement with each, a supply creel disposed about said post below said spindles, means rotatably mounted on said post and having a yarn guide surface interposed between said creel and said spindles, adapted upon unidirectional rotation to cause yarn from supply packages in said creel to traverse take-up bobbins on said spindles, and means for driving said belt and for rotating said last-mentioned means.

5. The machine according to claim 4 wherein said last-mentioned means includes means for cyclically varying the ratio of the rate of travel of the spindle drive belt to the rate of rotation of the traversing means.

6. The winding machine according to claim 4 including fixed yarn guide means positioned adjacent the path of travel of the yarn guide surface of said traversing means for preventing displacement of the yarn path in the direction of

travel of the yarn guide surface of said traversing means.

7. The winding machine according to claim 4 including a flat ring mounted on said platform and carrying said spindle mounts and cooperating means on said ring and platform permitting limited adjustment of the orientation of said spindle mounts by rotation of said ring about the axis of said post.

8. The winding machine according to claim 1 including an individual brake for each spindle and manually operable means for operating said brake to off and set positions, said operating means including an over-center toggle linkage operative to hold said brake in set position.

9. A textile winding machine having a generally cylindrical configuration with respect to a vertical central axis, said machine including a cylindrical skirt, a supply creel supported from said skirt, a ring supported from said skirt above said creel, a plurality of yarn tension devices carried by said ring, a central support structure positioned at the axis of said skirt, a plurality of spindles arranged in a circle above said tension devices with their axes inclined to the horizontal, means supported from said structure for rotatably supporting said spindles, a traverse rotor rotatably mounted on said structure and disposed for rotation in a path between said tension devices and said spindles, drive means for said spindles and for said traverse rotor supported by said structure and individually operable brake means for said spindles.

10. The machine of claim 1 wherein means are associated with said spindles for supporting said take-up bobbins in driving engagement therewith, said means being adjustable axially of said spindles whereby precise positioning of said bobbins with respect to said rotor can be obtained.

11. The machine of claim 4 wherein each of said spindles is provided with a take-up bobbin support having a threadwise axial adjustment with respect to its spindle to provide precise positioning of said bobbins with respect to said yarn guide surface.

12. The machine of claim 11 wherein each take-up bobbin support is provided with a plurality of resilient spacer members against which the respective bobbins are seated and adapted to be driven by frictional engagement therewith.

13. The machine according to claim 8 wherein one link of the toggle linkage is a rigid member having an operating handle extending therefrom and the other co-acting link comprising a spring-type bail member.

NORMAN E. KLEIN.
